INVENTOR

ATTORNEY

UNITED STATES PATENT OFFICE.

ZALA RIDDLE, OF SAN FRANCISCO, CALIFORNIA.

DIRECTION SIGNAL.

Application filed April 2, 1920. Serial No. 370,791.

To all whom it may concern:

Be it known that I, ZALA RIDDLE, a citizen of the United States, residing at San Francisco, in the county of San Francisco and State of California, have invented new and useful Improvements in Direction Signals, of which the following is a specification.

This invention relates to switches for direction signals.

In carrying out my invention, I provide a lamp in each circuit, the lamps being of different color and adapted to be singly lighted upon closing of a certain circuit.

The nature and advantages of the invention will be better understood when the following detail description is taken in connection with the accompanying drawings, the invention residing in the construction, combination and arrangement of parts as claimed.

In the drawings forming part of this specification, like numerals of reference indicate similar parts in the several views and wherein:

Figure 1 is a circuit diagram of the device controlled by a suitable switch.

Figure 2 is a sectional view taken through the switch.

Referring to the drawings in detail, A and B respectively, indicate solenoids which are connected in separate circuits including a switch of the construction illustrated in Figure 2. Upon reference to this figure it

will be noted that the switch mechanism is arranged within a casing 21 provided with a screw threaded detachable cover 22 the latter having an enlarged central opening 23 to permit of proper movement of the

manipulating handle or member 24 of the switch. This manipulating element 24 is

yieldably supported by the coil spring 25 upon a base 26 for rocking movement, through the medium of the plate 26', the

end convolution of the coil spring bearing against the plate and the base respectively, and carries the movable member 27 of the switch, which in this specific instance is in the form of a disk as shown. The coil

spring is arranged within the housing 21' which has its top wall slotted as at 22' to further permit the proper movement of the manipulating handle 24. Surrounding the lower edge of the housing then is a flange

23' for securing said housing to the base 26. Projecting from the base 26 are spaced

groups of fixed contact members, each group being distinguished by the characters C, D and E respectively. The group C includes two contacts 29 and 30 respectively, a similar number of contacts being embodied in the group D and designated by the numerals 31 and 32 respectively, while in the group E there are three of such contacts indicated at 33, 34 and 35 respectively. The contact 30 of the group C, the contact 34 of the group E and the contact 32 of the group D are all offset adjacent their free ends to provide a retaining or locking element 24' in contacting engagement therewith if so desired. The contact 30 of the group C is connected with the adjacent contact 33 of the group E by means of the curved metallic strip 36, while the contact 32 of the group D is connected with the adjacent contact 35 of the group E by means of a similar strip 37. The movable contact 27 being carried by the manipulating element 24 which is mounted for rocking movement, is disposed to be moved into engagement with either group of contacts C, D, and E.

In practice, when the movable contact 27 is moved into engagement with the contacts of the group C, current flows from the battery 40 through the wire 41 to the switch, energizing the solenoid A. The current also passes through the wire 42 to the lamp 43. The current passes through the lamp 43 and wire 44 to the return 45, thence through the switch for the lights indicated at G and back to the battery through the wire 46. Obviously, the plate or strip 36 is energized by the contact 30, to which plate or strip the solenoid A is associated, while the wire 42 connects the lamp 43 with the contact 29.

When the movable contact 27 is brought into engagement with the fixed contacts of the group D, the plate or strip 37 is energized. The solenoid B being associated with this plate or strip 37 is also energized. The current in this instance passes from the battery 40 to the wire 41, then to the switch energizing the strip 37 and the solenoid B as stated. The current then passes through the switch and wire 47 to the lamp 48 which is of a different color from the lamp 43. The current passes through the lamp to the common return 45 and back to the battery in the manner above stated.

When the contact 27 is moved into en-

gagement with the contacts of the group E, both the strips 36 and 37 are energized, energizing both the solenoids A and B respectively. The current in this instance passes from the contact 34 through the wire 50 to the lamp 51, the latter being of a different color than either of the lamps 43 and 48. The current passes through the lamp 51 and the common return 45 back to the battery 19 as above outlined.

The switch is simple in construction, and both positive and efficient in operation.

While it is believed that from the foregoing description the nature and advantages of the invention will be readily apparent, I desire to have it understood that I do not limit myself to what is herein shown, as the same is merely illustrative of the principle of operation, and that such changes 20 may be resorted to when desired as fall within the scope of what is claimed.

What is claimed is:

A switch for automobile signalling devices comprising a casing, a cover provided 25 with an enlarged opening and threadedly mounted on the casing, a base secured with-

in the casing and being spaced and arranged parallel with the bottom thereof, a housing provided with a slotted top wall and an offset flange securing said housing to the base, 30 a plate engaging the top wall of the housing and adapted to normally close the slot therein, a coil spring arranged contrally within the housing and having its end convolution bearing against the plate and base 35 respectively, a swinging handle rising from the plate and being yieldably supported by the spring through the medium of the plate, said handle projecting through and beyond the slot in the top wall of the housing and 40 through and beyond the opening of the cover, a disk arranged within the casing and carried by said handle intermediate of its ends, a plurality of stationary contacts secured to said base and arranged in the path 45 of the disk and an offset portion arranged on the free ends of some of said stationary contacts and inclined toward the housing as and for the purpose specified.

In testimony whereof I affix my signature.

ZALA RIDDLE.
